UNITED STATES PATENT OFFICE.

CHARLES ADLER, JR., OF BALTIMORE, MARYLAND.

RAILWAY-CROSSING SIGNAL.

Application filed September 29, 1920. Serial No. 413,533.

To all whom it may concern:

Be it known that I, CHARLES ADLER, Jr., a citizen of the United States, residing at Baltimore, in the county of Baltimore and State of Maryland, have invented certain new and useful Improvements in Railway-Crossing Signals, of which the following is a specification.

This invention relates to signal devices for railway crossings and the like, and it has for one of its primary objects the provision of an improved apparatus of the character described which is simple in character, efficient in operation and requires but a minimum of power for operation.

Still another object of my invention resides in the provision of an improved device of the characteristics specified which will automatically turn to stop to the highway in case the apparatus is inoperative for some reason.

My invention also contemplates a simple arrangement of parts which can be readily protected from the weather.

The foregoing, together with such other objects as may hereinafter appear, or are incident to my invention, I obtain by means of a construction which I have illustrated in preferred form in the accompanying drawings, wherein:

Figure 1 is a diagrammatic view partially in elevation and partially in section, illustrating the application of my improvements; Figure 1^a is an end elevation of Figure 1; Figure 2 is a section taken on the line 2—2 of Figure 1 on an enlarged scale; and Figure 3 is a section on the line 3—3 of Figure 2, showing the parts in another operative position.

Referring now to Figures 1 and 3, the reference numeral 7 indicates the railway which is crossed. The crossing apparatus, indicated as a whole by the reference letter A, is supported on a bell post or other suitable standard 8 by means of a bracket 9 which may be of any preferred construction. The signalling apparatus comprises a target or other form of signal member 10 mounted on a vertically disposed shaft 11, the upper end of which is passed through an aperture 12 in the bracket 9. The upper end of the shaft is enclosed in a chamber 13 and it is supported by means of two bearings 14 and 15, the former being a simple side bearing and the latter being a combination side and thrust bearing. Both of these bearings are

preferably of the ball type, the arrangement of chamber and bearings being such that the latter as well as the shaft may be assembled or taken down in a simple and accessible manner. It will be noted that the central member of the thrust bearing 15 extends radially around the periphery of the shaft 11 to an extent sufficient to cover that portion of the aperture 12 which is not filled by the shaft 11. This construction effectively prevents rain, ice or snow passing entirely through the aperture 12, and entering the chamber 13.

The operating mechanism for the shaft 70 comprises a solenoid 16 or other suitable electro-magnetic device, the armature of which is connected through the medium of a link 17 with the arm or pin 18 on the shaft; and the weight 20 carried on an arm 75 21 pivoted in a bracket 21' on the chamber 13, such arm being connected with the pin 23 of the shaft by a link 22, suitable universal joints 24 being provided to permit flexure during turning of the shaft, and suitable apertures 17^a and 22^a being formed in the wall of chamber 13, permitting the passage of the links 17 and 22.

The operation is as follows: The solenoid is preferably on a closed circuit and is thus normally energized, holding the signal "clear" to the highway, i. e., at right angles to the position shown in Figure 1. In this position the actuating parts are in the position shown in Figure 3. On the approach of a train, the circuit is broken in any preferred manner, as is well understood in this art, and the solenoid is deenergized whereupon the weight 20 automatically operates to turn the shaft and signal 90° to "stop" position to the highway. When the circuit is again established, the solenoid operates to turn the shaft back to initial position. Should the electrical apparatus become inoperative, the weight will automatically shift 100 the signal to "stop" position, thus always ensuring a danger at all times.

It will be understood that the bell 19 is suitably connected and that the signal arms are provided with shrouded lamps 25, and that the shaft is also provided with a lamp or lamps 26 covered by a shroud 27 open at the ends. The lamps may be operated on any of the systems well known in this art.

It will be apparent that the arrangement 110 is such that but a minimum amount of power will be required to rotate the shaft 11

and its associated parts and as a result a light weight 20 will suffice to return the parts to position. The current required to overcome the weight and turn the shaft will thus be small. Furthermore, it will be noted that the parts are easy to protect against the weather, to which end I provide a shell or casing 28 which houses the actuating parts. If the exposed portions of the shaft 10 and the target become somewhat loaded with snow or ice it will be apparent that the effect will be negligible as compared with the increase in leverage which results under such conditions in the swinging arm 15 signals ordinarily employed.

Other advantages will readily occur to those familiar with the art.

I claim:

1. A crossing signal comprising a support, a rotatable shaft depending therefrom and provided with a signal arm adjacent its lower end, a chamber enclosing the upper end of said shaft, bearings for said shaft at separated points in said chamber, means for 20 rotating said shaft, and a housing covering said chamber and said shaft operating means.

2. A crossing signal comprising a support, a rotatable shaft extending through 30 said support and provided with a signal arm adjacent its lower end, a chamber enclosing the upper end of said shaft, said chamber carrying shaft bearings at its top and bottom, apertures in said chamber,

means extending through one of said apertures and adapted to rotate the shaft in one direction, and means extending through another aperture and adapted to rotate the shaft in an opposite direction, substantially as described. 35

3. A crossing signal comprising a support, a rotatable shaft depending therefrom and carrying a signal arm on its lower portion, a chamber carried by said support and enclosing the upper end of said shaft, means for rotating said shaft in one direction a bracket mounted on a wall of 45 said chamber, and means supported by said bracket for rotating the shaft in another direction.

4. A crossing signal comprising a support, a rotatable shaft depending therefrom and carrying a signal arm on its lower portion, a chamber carried by said support and enclosing the upper end of said shaft, means for rotating said shaft in one direction, a bracket mounted on a wall of said chamber, and means supported by said bracket for rotating the shaft in another direction, said means comprising an arm 55 pivoted to said bracket and carrying a weight at its lower end, and a link secured to said shaft and pivoted to the upper end of said arm, substantially as described.

In testimony whereof, I have hereunto signed my name.

CHARLES ADLER, Jr.
